TRAIN DISPATCHING SYSTEM FOR
RAILROADS

Bernard J. Schwendt, Cleveland, Ohio, assignor
to General Railway Signal Company, Roches-
ter, N. Y.

Application November 17, 1927, Serial No. 233,845

26 Claims. (Cl. 246—3)

This invention relates to train dispatching systems of the type in which the dispatcher communicates with the engineers, that is dispatches the movement of trains, through the medium of 5 wayside signals.

In a train dispatching system of the kind mentioned, a single train dispatcher preferably has charge of traffic over a track section containing a large number of passing sidings, and controls 10 isolated interlocking plants which are also located at various points along such railway track section. That is, the wayside stations are so located with respect to the dispatcher that the control circuit for the most distant wayside station in a particular direction invariably passes by all of the nearer wayside stations in that direction. In a system where the wayside stations are distributed in a manner as just mentioned, a great economy in line wires would result if the 15 same circuit wires could be used for the control of signals at, and the indication movement of trains by, each and every one of the wayside stations.

In accordance with the present invention, it is 25 therefore proposed to control the wayside signals, operate the switches and the like, of all the wayside stations in a particular stretch of track, through the medium of code responsive selector relay or relays of any suitable and well known 30 construction; whereby a particular traffic controlling device may be operated to a particular position in response to the transmission of a particular code of impulses to all of the various wayside stations, suitable code responsive 35 selectors being provided at each wayside station for this purpose.

The operation of any one of a plurality of wayside signals and power operated switch machines through the medium of a single control circuit 40 and a plurality of distinctively responsive code responsive selectors as just explained, is a comparatively simple problem. The principal difficulty encountered in dispatching the movement of trains through the medium of wayside signals 45 resides in the provision of means for manifesting to the train dispatcher the progress of the various trains along the track over comparatively few line wires. This difficulty arises from the fact that automatically operated calling keys and 50 code responsive selectors alone can not be used, for if the progress of trains is reported to the train dispatcher by the condition of occupancy of the various track sections, it is possible that two or even three track sections may 55 become occupied or unoccupied at the same in-

stant and if this simultaneous change in traffic conditions were transmitted to the train dispatcher by distinctive codes of impulses, a jumbled up code would result. In other words provision must be made whereby it is impossible 5 for a plurality of codes to be transmitted to the dispatcher's office simultaneously.

It is therefore proposed in accordance with the present invention to not only control the wayside signals and switch machines of all of the 10 various wayside stations by distinctive codes received by specific code responsive selector relay or relays over the same line circuit, but to transmit over the same line circuit information to the dispatcher's office as to the occupancy of various 15 track sections, positions of signals, the positions of track switches, derails, and the like, and to provide suitable lock-out means, whereby if conditions are such that two distinctive codes are attempted to be transmitted at the same time, 20 one of these indications is entirely held up until the other has been transmitted, after which the lock-out apparatus will permit the said one code to be transmitted to the dispatcher's office over 25 the same circuit.

Other objects, purposes and characteristic features of the invention will in part be apparent from the accompanying drawings, forming a part of this application, and will in part be described in the specification hereinafter.

In describing the invention in detail reference will be made to the accompanying drawings:—

The main drawing is contained on two sheets and is designated Figs. 1A and 1B, respectively. The portion of the drawing designated Fig. 1A 35 illustrates conventionally apparatus located in the dispatcher's office and embodying the present invention, and the drawing designated Fig. 1B illustrates conventionally apparatus of the train dispatching system embodying the present 40 invention located along the trackway; and

Fig. 2 shows a slight modification of the invention.

In order to more readily understand the detail features of the present invention as more 45 specifically pointed out hereinafter it is deemed expedient to first briefly point out what the various features are. In order to transmit distinctive codes over a single line circuit connecting a certain wayside station with the dispatcher's 50 office, say in response to the dropping of a track relay, it is necessary to operate a so called "calling key" or "code transmitter". In order to be sure that this code is actually transmitted to the dispatcher's tower it is proposed in accordance 55

with the present invention to provide a stick relay which controls the motor for operating this calling key, and it is proposed to arrange the circuits so that this stick relay will remain 5 energized until the code has actually been transmitted to the dispatcher's office, after which the stick relay will drop and again stop the motor driven calling key or code transmitter.

In order to prevent calling keys of the several 10 waystations to transmit codes over the same line circuit at the same time I have provided a lock-out circuit or pilot circuit, whereby only one of the waystation calling keys may transmit a distinctive code to the train dispatcher's 15 office at one time. In the particular arrangement shown this lock-out combination comprises a plurality of relays each having an upper and lower winding, of which all of the lower windings are connected in series. If a 20 particular waystation apparatus is in condition to transmit a code to the dispatcher's office the upper winding of the relay of that particular waystation is energized by current which tends to cause the normally energized relay to assume 25 its retracted position. When this occurs the lower winding of this relay is cut out of the pilot wire or lock-out circuit and an additional source of current is put in this lock-out circuit. With this additional voltage in the 30 circuit the current flow in this circuit is sufficient to maintain all of the other double winding pilot relays energized in spite of the application of opposing current to their upper winding, so that even though the upper winding of any one of 35 the other relays is energized with neutralizing current such relay will not assume its de-energized position. The arrangement is thus such that the dropping of one of these lock-out relays to their retracted position will cause the lock-out 40 circuit to be energized by excess current, thereby preventing dropping of any other lock-out relay. The arrangement is such that a code can not be transmitted from a waystation to the dispatcher's office unless such lock-out relay assumes 45 its de-energized position.

Another of the features of the waystation apparatus resides in the provision of a synchronizing relay which can only close the coding circuit for that particular waystation at the beginning of 50 a cycle of operation of the code transmitter and this synchronizing relay is also constructed and controlled so as to again open this code transmitting circuit at the end of the transmission of a distinctive code of impulses.

55 The waystation apparatus also includes a hold-over relay which is constructed and operated so that it is in cooperation with a hold-over cam of the code transmitter and will stop the code transmitter at the end of the first cycle in which a 60 code is actually being transmitted to the dispatcher's office. These various essential characteristic features should be borne in mind in connection with the following detailed description of the invention.

65 General description

Although the present invention in practice would, as a rule, be applied to a stretch of track having from 10 to 20 passing sidings or waystations, only a portion of such stretch of track, and a portion of the associated apparatus, has been shown in the drawings. Referring to Fig. 1B a stretch of single track O together with the adjacent ends of two passing sidings PS¹ and PS², of 70 the railway track have been shown. At each end 75

of each passing siding is provided the usual track switch, those shown being designated S¹ and S², and these track switches are preferably operated by power operated switch machines SM having a corresponding exponent.

These track switches are provided with the usual detector track circuit, the one for the track switch S¹ includes the detector track relay 2DR and a track battery 10, and the detector circuit for the track switch S² includes the track relay 10 5DR and the track battery 11. The starting signals associated with the track switch S¹ have been designated 2 and 2^a and are set at the entrance to the detector track circuit for that direction of traffic which they govern, and the entering 15 signals have been designated 1 and 1^a and are located at the entrance of the detector track circuit for the direction in which they govern traffic. In the same way, the starting signals for the track switch S² have been designated 5 and 5^a respectively, and the entering signals have been designated 6 and 6^a. Although, in practice, there would as a general rule be a plurality of pairs 20 of intermediate signals, only the intermediate signals 3 and 4 have been shown. It should be noted 25 that the signals for west bound traffic have been designated by odd numbers, whereas the signals for east bound traffic have been designated by even numbers. The signal system embodying the signals shown is one of the absolute-permissive-block type, and these signals are controlled in accordance with traffic conditions, the condition 30 the control relay Z and the position of the switch machines SM, all in a manner as more particularly disclosed in the application of Sedgwick N. Wight 35 Ser. No. 120,423 filed July 3, 1926, which corresponds to Australian Patent No. 7,777 of 1927. For the purposes of the present application the 40 apparatus for controlling these various signals in accordance with traffic conditions has been emitted, and the superimposed control thereof in response to the energized condition of the control 45 relay Z and the position of the switch machine SM has been conventionally shown by dotted lines. It should however be understood that the 50 present invention may be superimposed on any type of signal system, double track as well as single track. It may be pointed out here that the various relays associated with the track switch 55 S¹ contain a reference letter having an exponent 1, and that the corresponding relays associated with the track switch S² are designated by like reference characters having the distinctive exponent 2.

In the particular embodiment of the invention 55 illustrated the usual telephone line TEL is simplex by the provision of impedance units 15, 15^a, 15^b, 15^c etc., to the midpoint of which suitable circuit portions are connected. In addition to this telephone line TEL there is provided a common 60 return wire C, and a lock-out wire LO which extend throughout the entire stretch of trackway controlled by a particular train dispatcher. It may be pointed out here that the switch machines SM¹ and SM² are provided with racks 65 16¹ and 16², which upon movement of such switch machine from one extreme position to the other, causes any suitable number, such as two taps to be sounded in the telephone or loud speaker T located at the dispatcher's office when the switch 70 machine starts its operating stroke and again sounds two more taps when such switch machine has completed its stroke. This is accomplished by intermittently connecting the battery 17 across the telephone line TEL. 75

In the dispatcher's tower or office conventionally shown by the dotted rectangle DT is preferably suitably mounted, as on a table, a miniature track layout corresponding to that of the portion of the railway system over which that particular dispatcher has supervision. The portion of the miniature track layout shown comprises a single track section o corresponding to the single track section O shown in Fig. 1B of the drawings. On this miniature track layout are provided, as for instance for the switch S¹, a red light R¹, and a green light G¹ to indicate the occupancy and unoccupancy respectively of the detector track circuit associated with the switch S¹. Similarly lamps R² and G² are provided at the exit end of the single track section o. With both of these lamps extinguished unoccupancy of the detector track circuit is manifest, with the lamp R¹ lighted occupancy of this detector track circuit is indicated and when both the red lamp R¹ and the green lamp G¹ are lighted manifests that the detector track circuit has been occupied and has since been cleared. These lamps may be colored as desired, and the lamp G may be entirely omitted if desired.

Dispatcher's control mechanism.—Referring to the apparatus for controlling the switch machines and signals associated with the switch S¹, and bearing in mind that with the relay Z¹ energized to its normal position the switch machine SM¹ will assume its normal position, and if so, the continued energization of the relay Z¹ to normal will clear the signals 1 or 2 depending upon whether the signals 5 and 5^a are at clear or stop, all of which has been described in detail in the application of Wight above referred to. All that need to be considered in the present application to understand the application of the present invention is the manner in which the control relay Z¹ is controlled from the dispatcher's office DT.

In the dispatcher's office there are provided cranks or levers LN¹, LS¹ and LH¹, which if successively separately operated through a complete cycle will cause the code responsive relay CCR^a at the way station S¹ to apply the positive terminal B of a suitable battery to the wires 20, 21 and 22 respectively. That is, if the lever LN¹ is operated through its cycle the wire 20 is momentarily energized thereby picking up the normal route relay NR¹; if the lever LS¹ is operated through a complete cycle the code responsive selector CRR^a will momentarily energize the siding route relay SR¹, which will thereafter be maintained energized through a stick circuit; and if the stop lever LH¹ is operated through a complete cycle the stop relay ST is momentarily energized, thereby dropping the relay Z¹, and momentarily opening the stick circuit of the normal route relay NR¹ or siding route relay SR¹ depending upon which one of these route relays is energized at the time. The pick-up circuit for the normal route relay NR¹ completed upon operation of the lever LN¹ may be traced as follows: beginning at the terminal B of a suitable source of direct current, wire 25, selector contact 26 of the selector CRR^a, wires 20 and 27, winding of the route relay NR¹, wires 28, 29 and 30, to a common return wire C connected to the other terminal of said source of current. With this route relay momentarily picked up the following stick circuit is completed:—beginning at the terminal B, wires 25 and 31, back contact 32 of the stop relay ST, wires 33 and 34, back contact 35 of the siding route relay SR¹, wire 36, front stick contact 37 of the normal relay NR¹, wires 38 and 27, winding of the route relay NR¹,

wires 28, 29 and 30, to the other terminal N of said source. The various code responsive selector relays forming elements of the present invention may be of any suitable construction, such for instance as shown in the patent to Field #1,343-526 dated June 15, 1920 and their specific construction does not form a part of the present invention, the present invention merely including such selectors as elements thereof.

Assuming for the moment that the relays NR¹, SR¹ and ST are in their normal de-energized condition, the pick up circuit completed for the siding relay SR¹, when the lever LS¹ is operated, may be traced as follows:—beginning at the terminal B, wire 25, selector contact 40 of the code responsive selector CRR^a, wires 21 and 41, winding of the siding route relay SR¹, wires 42, 29 and 30, to the common return wire C connected to the other side of the source containing terminal B. With this siding route relay SR¹ once energized the following stick circuit is completed to maintain it energized:—beginning at the terminal B, wires 25 and 31, back contact 32 of the stop relay ST, wires 33 and 43, back contact 44 of the normal route relay NR¹, wire 45, front stick contact 46 of the siding route relay SR¹, wires 47 and 41, winding of the siding route relay SR¹, wires 42, 29 and 30, to the common return wire C.

It should be noted that the stick circuits for both of the route relays NR¹ and SR¹ include the back contact 32 of the stop relay ST, so that momentary energization of the stop relay ST in response to operation of the lever LH¹, causes the stick circuit for the route relays NR¹ or SR¹ depending upon which one is energized to be momentarily broken thus causing such route relay to drop. The energizing circuit for the stop relay ST comprises the following:—starting at B, wire 25, selectors contact 48 of the code responsive relay CRR^a, wire 22, stop relay ST, wires 49 and 40, 30, to the common return wire C.

Operation of dispatcher's control mechanism

Let us assume that the dispatcher wishes to allow a train standing on the siding of passing siding PS¹ to move eastwardly in the single track section O, and in order to do so wishes to operate the track switch S¹ to the take-siding position. The operator will operate the lever LS¹ through a complete revolution, and thereby through a suitable escapement or by time controlled mechanism preferably provided for each one of the levers, allows the calling key associated with this lever LS¹ to transmit the desired code, namely the code which will close the selector contact 40 of the selector CRR^a, but which code will not close any other selector contact of the entire system. This will cause the siding route relay SR¹ to be picked up and stuck up for reasons already given and whereby close the following circuit for the control relay Z¹;—beginning at the terminal B, contact 50 of the siding route relay SR¹ in its raised position, wire 51, contact 52 of the route relay NR¹ in its lower position, wire 53, back contact 54 of the stop relay ST, wire 55, winding of the relay Z¹, wire 56, back contact 57 of the stop relay ST, wire 58, contact 59 of the route relay NR¹ in its lower position, wire 60, contact 61 of the route relay SR¹ in its raised position, to the negative terminal N of the source containing positive terminal B. With this circuit completed the control relay Z¹ will assume its left hand dotted position, and will thereby operate the switch machine SM¹ to the take-siding position through circuits conventionally shown by a dotted line 62. If the 75

switch machine is operated rack 16¹ intermittently applies direct current across the telephone line TEL through the following partial circuit:— starting at one telephone wire, wire 63, battery 17, 5 wire 64, rack 16¹, contact 65, wire 66 connected to the other wire of said telephone line. This application of potential to the telephone line will cause a click in the telephone or loud speaker T located in the dispatcher's office, two such clicks being 10 given when the switch machine is started and two more clicks being given after the switch machine has completed its operating and locking stroke. Assume that the starting signals 5 and 5^a at the 15 exit end of the single track section O are both at stop, the starting dwarf signals 2^a is cleared as soon as the switch machine SM¹ has assumed the take-siding position, and the train may then proceed into the single track section O.

Let us now assume that the dispatcher wishes 20 to return the track switch S¹ to the normal main track position. In this case it will not be necessary for the operator to first operate the stop lever LH¹ to effect de-energization of the relay Z, but he may operate the normal lever LN¹ and 25 thereby de-energize the route relay SR¹, energize the route relay NR¹, and cause the control relay Z¹ to assume its main track energized position. That is, operation of the normal lever LN¹ causes the pick-up circuit for the normal route relay 30 NR¹, heretofore traced, to be completed, thereby causing the stick circuit for the siding route relay SR¹ which relay at this time is still stuck up through its stick circuit, to be broken at the contact 44 of route relay NR¹, so that the route 35 siding relay SR¹ assumes its retracted condition and thereby allows the stick circuit for the route relay NR¹, heretofore traced, to be completed. With the normal route relay NR¹ picked up and stuck up, the following circuit for energizing the 40 control relay Z¹ to its normal straight track position, in which current flows in the reverse direction from that which was flowing when the relay Z¹ was energized to the reverse position, to be completed;—beginning at the terminal B, contact 45 50 of the siding route relay SR¹ in its lower position, wire 76, contact 59 of the route relay NR¹ in its raised position, wire 58, back contact 57 of the relay ST, wire 56, winding of the control relay Z¹, wire 55, back contact 54 of the relay ST, wire 53, contact 52 of the route relay NR¹ in its raised position, wire 77, contact 61 55 of the route relay SR¹ in its lower position to the terminal N. The completion of this circuit causes the switch machine SM¹ to be returned to its normal straight track position, and if the control 60 relay Z is then de-energized by reason of momentary energization of the stop relay ST, due to operation of the stop lever LH¹, all of the signals 1, 1^a, 2 and 2^a will again assume their normal stop position. It may be mentioned at this 65 point that during the transmission of a distinctive code from the dispatcher's office to a waystation, the code relay COR located in the dispatcher's office is energized through one or the other of the various lever contacts 67, 68, or 69, as a result of which excess energy is applied to the lock-out circuit LO, whereby all of the various waystation transmitters CT are locked out, so to speak, so that the wayside apparatus cannot 70 simultaneously transmit a code to the dispatcher. This feature will be described more in detail under the heading "Operation of indicating and OS-ing mechanism".

Indicating or OS-ing mechanism.—The indicating or OS-ing mechanism associated with the

detector track circuit of switch S² will, for convenience, only be described, and like parts of the apparatus associated with the detector track circuit of switch S¹ will be assigned like reference characters having distinctive exponent. In the 5 tower or dispatcher's office is provided a code responsive relay CRR² of which the selector contact 70 is closed when a code is transmitted thereto by the red code wheel RW, and the selector contact 71 of which is momentarily closed 10 if code is transmitted by the green code wheel GW of the automatic calling key or code transmitter CT². Obviously momentary closure of these selector contacts 70 or 71 will cause the relay RG² or RR² to be picked up and stuck up, 15 and thereby lighting the lamps G² or R², respectively. With the code transmitter CT² are associated various auxiliary devices, such as, the red stick relay RS², the green stick relay GS², the pick up relay PU², the hold-over relay HO², the 20 synchronizing relay SYN², the green code cam relay GK and the red code cam relay RK.

The code transmitting machine CT² is driven by the motor M and includes a stop cam SC, hold-over cam HOC and a starting cam STC. 25 As already mentioned in a general way, this system includes a lock-out circuit LO which includes a pilot relay PR for every waystation and code transmitter. Only two of these relays PR¹ and PR² have been shown. These relays, such as 30 PR¹, although they are only two position relays have polar armatures so that current of a particular polarity is required to pick up the various contacts shown and if current of reverse polarity of a sufficient value to neutralize the current of the lower winding is simultaneously applied to the upper winding thereof, the movable element of this relay together with its various contacts will assume their retracted position. It 35 may be pointed out at this time that all of these relays PR have their lower windings connected in series in the lock-out wire LO in stick fashion, that is these lower windings include in series therewith the front contact of these relays; and further at the remote end of the section under the supervision of the dispatcher this lock-out wire LO is connected to the common return wire C as shown by the dotted line 73, also upon the dropping of one of these relays, as PR², as by 40 the application of neutralizing current to its upper winding, the lower winding is cut out of the lock-out circuit and the battery 74² is substituted therefor, all through the shifting of contacts 75², 90² and 93². This will cause the remaining pilot relays PR¹ to be energized by excess current, so that the application of neutralizing current to any one of them will not cause 45 such relay to assume its retracted position.

Operation of indicating or OS-ing mechanism.—The normal circuit for the various pilot 50 or lock-out relays PR may be traced as follows:— beginning at the battery 80 wires 137 and 139 located in the dispatcher's office, back contact 81 of the cut out relay COR, wires 82, LO and 83, front contact 90¹ of the relay PR¹, wire 85, lower 55 winding of the relay PR¹, wire 86, front contact 93¹ of the relay PR¹, wires 88, LO and 89, front contact 90² of the relay PR², wire 91, lower winding of the relay PR², wire 92, front contact 93² of the relay PR², wires 94 and LO, through the 60 various other lock-out relays PR, conventionally shown by the dotted line 73, to the common return wire C connected through wire 95 to the negative terminal of the battery 80. In addition 65 to this provision for the energization of the vari- 70 75

ous pilot relays PR the upper winding of these relays, such as the relay PR², is also normally energized through the following circuit:—beginning at the positive terminal B of a suitable battery, contact 96, wires 97 and 98, back contact 99 of the relay HO, wire 121, upper winding of the relay PR², wire 122, back contact 123 of the relay HO, wire 124, contact 125 operated by the cam HOC, to the negative terminal N of said battery.

Let us now assume that a train has just entered upon the detector circuit containing the detector track relay 5DR, and has caused the contacts 100 and 101 of this relay 5DR to assume their retracted position. This will cause the pick up relay PU² to move its polar contact 102 to the reverse dotted position and thereby momentarily complete a pick-up circuit for the red stick relay RS², which circuit may be traced as follows:—beginning at the positive terminal B of a suitable battery, polar contact 102 engaging the one way contact 103 of the pick up relay PU², wires 162 and 105 winding of the red stick relay RS² to the negative terminal N of the said battery. With this red stick relay RS² momentarily picked up the following stick circuit for this relay is completed;—beginning at the negative terminal N of the said battery, winding of the relay RS², wires 105 and 106, front contact 107 of the red stick relay RS², wires 108 and 109, and then through either of the following two branches; (1) wires 167 and 111, and front contact 112 of the pilot relay PR², to the terminal B, and (2) through wire 113 and normally closed contact 114 of the stop cam SC to the terminal B. This stick relay RS² is thus stuck up until its stick circuit is broken. It should be noted that the one way contacts 103 and 115 are pivotally supported at the pivot point 116 and that they are yieldably held in this position shown by the tension spring 117. From this construction it is apparent that if the contact 102 moves from its normal position to its dotted position it engages only the contact 103, and if it is moved from its dotted position to its normal position it engages only the contact 115.

With the red stick relay RS² stuck up as just explained, the code transmitter CT² is operated through suitable reduction gearing (not shown) by the motor M, the energizing circuit of which motor may be traced as follows:—beginning at the positive terminal B of a suitable battery front contact 118 of the red stick relay RS², wire 178^a, winding of the red code cam relay RK, wires 119 and 120, motor M, to the negative terminal N of said battery. The code transmitter CT² is started upon its operating cycle in a direction as indicated by the arrow. Upon beginning a cycle of operation the starting cam STC of this transmitter CT² first closes its contact 130, and immediately thereafter causes the hold-over cam HOC to reverse its pole changer contacts 96 and 125. The reversal of these contacts 96 and 125 causes the potential applied to the upper winding of the relay PR² to be reversed, and since this current is in excess as to ampere turns or at least equal to that of the current flowing in the lower winding of this relay PR², this relay PR² will assume its de-energized position. This will cause its lower winding to be entirely cut out of the lock-out circuit and the lock-out circuit to be energized by excess current derived from the battery 74^a, which is now connected in series with the battery 80 in the dispatcher's office.

At substantially the same time that contacts

96—125 are shifted from normal, the contact 130 operated by the starting cam STC closes a pick up circuit for the synchronizing relay SYN². This circuit may be traced as follows:—Starting at the positive terminal B of a suitable battery, contact 112 of the pilot relay PR² in its de-energized position, wires 131 and 132, winding of synchronizing relay SYN², wires 133 and 134, contact 130 operated by the starting cam STC to the negative terminal N of said battery. It should be noted that even though the pilot relay PR² is now in its de-energized position the red stick relay RS² still has its stick circuit completed through the stop contact 114 operated by the stop cam SC. With the synchronizing relay SYN² energized a code transmitting circuit through the red code wheel RW is completed, the red code cam relay RK being energized through the circuit heretofore traced. This code circuit may be traced as follows:—beginning at the battery 80 located in the dispatcher's tower DT, wires 137 and 138, battery 140, wire 141, winding of the master relay MR, wires 142, 143, and 144 to the midpoint of the simplex impedance 15 of the telephone line TEL, through the two telephone wires in multiple to the balancing impedance 15^a, wire 145, front contact 146 of the synchronizing relay SYN², wires 147 and 148, red code wheel RW, wire 149, front contact 150 of the relay RK, wires 151 and 152, to the common return wire C connected by wire 95 to the negative side of battery 80. The code transmitted by the red code wheel RW causes the necessary number and properly spaced impulses to be transmitted to close the selector contact 35 70 of the code responsive relay CRR² in the dispatcher's office, thereby picking up the red relay RR² through wires 154 and 155. This relay RR² is then stuck up through a stick circuit including its own front contact 156, wire 157, the normal closed push button contact 158, wire 159 and 155. With the relay RR² energized the red lamp R² is illuminated through the completion of the following circuit:—starting at B front contact 160 of the relay RR², wire 161, red lamp R², to the other terminal N.

It should be noted that during this transmission of the distinctive code to the tower the red stick relay RS² depends for its energization on the contact 114 operated by the stop cam SC. Near the end of the cycle of the operation of the code transmitter CT² this stop cam SC momentarily opens the contact 114, thereby interrupting the stick circuit for stick relay RS² and causing it to assume its de-energized position. Dropping of the stick relay RS² cuts energy off of the motor M and stops the code transmitter at the end of the complete cycle. Just prior to the completion of this cycle of operation of the code transmitter CT² the holdover cam HOC returns the contacts 96 and 125 to their normal position, thereby reversing the flow of current in the upper winding of the pilot relay PR², thereby causing this pilot relay PR², which is a polar relay, to again assume its normal energized position, and thereby removing the excess energy formerly supplied by battery 74^a and again connecting the lower winding of this relay PR² in the lock-out circuit LO. This picking up of the relay PR² interrupts the energizing circuit for the synchronizing relay SYN², thereby restoring this relay SYN² to normal. All of the code transmitting apparatus is now again in its initial and normal condition.

The operator has thus been informed by the

illumination of the red lamp R^2 that a train has entered upon the detector track circuit associated with track switch S^2 . The operator may then, if he so desired, depress the push button 158 and again extinguish the lamp R^2 , it being assumed that he has taken the necessary action in response to this train movement.

When the train again leaves the detector track circuit containing track relay 5DR the contacts 100 and 101 thereof will be returned to their normal position, thereby returning the pick-up relay PU² to its normal solid line position. This movement of the contact 102 of the pick-up relay PU² momentarily completes a pick-up circuit for 15 the green stick relay GS², which may be traced as follows:—beginning at the positive terminal B of a battery, polar contact 102, oneway contact 115, wires 162 and 163, winding of the green stick relay GS² to the negative terminal N of the said battery. With this relay GS² picked up it will be 20 stuck up through the following circuit:—beginning at the negative terminal N of the said battery winding of the relay GS², wires 163 and 164, front stick contact 165 of the relay GS², wire 166, 25 and then through the following two branches; (1) wire 111 and contact 112 of the relay PR², to positive terminal B, and (2) wires 167 and 113, and stop contact 114, to the positive terminal B. With the green stick relay GS² energized the 30 motor M and green code relay GK are energized through the following circuit:—beginning at the terminal B of a suitable battery, back contact 118 of the red stick relay RS², wire 170, front contact 171 of the green stick relay GS², wire 172, winding of the green cam relay GK, wires 173 and 120, motor M, to the other terminal N of said battery.

The function of transmitting the green code through the medium of the green code wheel GW under ordinary circumstances is the same as that 40 of transmitting the red code already explained, except as to the specific character of the code, so that this need not be specifically described. This green code of course picks up the relay RG², which in turn illuminates the green lamp G², corresponding parts and contacts associated with relay RG² have been assigned like reference characters with distinctive exponents *a* as those associated with relay RR². It may however be pointed out that the green code can not be transmitted until the red code has been transmitted, this because the energizing circuit for the green code relay GK is carried through the back contact 118 of the red stick relay RS². From this it is seen that if the red relay RS² is stuck up, and 50 the green relay GS² is also stuck up thereafter but before the red code has been transmitted, the transmission of the green code is held in abeyance until the red code has been transmitted after which both of these stick relays RS² and GS² 55 are de-energized and in this event no green code is transmitted.

As already pointed out heretofore, there is a possibility of two different detector track circuits becoming occupied at the same time, or for one 60 to be occupied at the same instant another is cleared, or two detector track circuits to be cleared at exactly the same time, and for this reason the transmitting mechanism at two different waystations may be initiated at substantially the same time.

In order to avoid two different code transmitters CT transmitting codes simultaneously, the lock-out circuit LO and the associated pilot relays PR have been provided. In order to get a 65 more clear understanding of this lock-out feature

of the present invention let us assume that the detector track circuit associated with switch S² is being occupied by a train at an instant when one of the other pilot relays, such as the pilot relay PR¹, is in its retracted condition, possibly because 5 the associated code transmitter is transmitting a code to the dispatcher's office at that particular time. The treading of the train in question upon the detector track circuit containing track relay 5DR causes this relay 5DR to be de-energized, the pick up relay PU² to be operated to the reverse dotted position, and the red stick relay RS² to be picked up and stuck up, in a manner as already described above. With the red stick relay RS² 10 picked up the energizing circuit for the red cam relay RK including in series therewith the motor M, heretofore traced, is completed. Although the completion of this circuit causes the code transmitter CT² to begin to operate, and thereby causes reversal of contacts 96—125, which contacts 96—125 reverse the polarity applied to the upper winding of the pilot relay PR², the reversal of the current flow in the upper winding of the relay PR² at this time will not affect the polarized armatures of this relay PR², because the lower winding of this relay is now energized by excess current, by reason of the fact that the battery 74¹ associated with the pilot relay PR¹ is now connected in the lock-out circuit LO so as to increase the current flow therein by reason of the 15 accumulated effect of the batteries 74¹ and 80. The code transmitter CT² operates through one or more successive cycles without transmitting a code, because the synchronizing relay SYN² is not picked up in spite of closure of the contacts 20 130 operated by the starting cam STC at the beginning of each cycle, this energizing circuit for relay SYN² being broken at the contact 112 of the pilot relay PR². Also, it should be noted that the code transmitter is not stopped at the end of its 25 first, or any other, cycle of operation, by reason of opening of stop contact 114 operated by stop cam SC. Although this contact 114 is opened at the end of each cycle, it does not open the stick circuit for the red stick relay RS², because the 30 other branch of this stick circuit for relay RS² including the contact 112 is intact and the relay RS² remains stuck up.

Let us now assume that at substantially the middle of the cycle of operation of the code transmitter CT², the pilot relay PR¹ is picked up, possibly because the code transmitting apparatus associated therewith has completed its code transmitting function. This picking up of the relay PR¹ at an intermediate point in the cycle of the 40 operation of the code transmitter CT² causes the relay PR² to be de-energized, (no excess energy existing in the lock-out circuit LO at this time), and with the synchronizing relay SYN² de-energized (the pilot relay having dropped during an 45 intermediate part of a cycle) the following circuit for the hold over relay HO is completed:—beginning at the terminal B of the suitable battery, back contact 112 of the pilot relay PR², wires 131 and 181, winding of the hold-over relay HO², wire 182, back contact 183 of the relay SYN² assuming its de-energized condition, to the negative terminal N of the said battery. With the hold-over relay HO² energized, the following supplemental 50 stick circuit for the red stick relay RS² is completed:—beginning at the terminal B of a suitable battery front contact 185 of the hold-over relay HO², wires 186 and 108, front stick contact 107 of the red stick relay RS², wires 106 and 105, 55 55 60 65 70 75 75

winding of this relay RS², to the negative terminal N of said battery. Also, with the hold-over relay HO² in its energized condition the upper winding of the pilot relay PR² is directly connected with the battery containing terminals B and N through contacts 98 and 123, so that the upper winding of the pilot relay PR² is supplied with bucking current tending to hold the polarized armature and associated contacts 75, 90, 93 and 112 of this relay PR² in their retracted position, in spite of the shifting of the contacts 98 and 125 associated with the hold-over cam HOC of the code transmitting mechanism at the end of the cycle under consideration.

15 As the code transmitter CT² now continues its operation and begins the next cycle, the starting cam STC closes its contact 130, and in so doing picks up the synchronizing relay SYN² through a circuit heretofore traced. The picking up of the synchronizing relay SYN² breaks the energizing circuit for the hold-over relay HO², thereby re-establishing a circuit for the upper winding of the pilot relay PR² which includes the contacts 96—125 of the hold-over cam HOC. With the synchronizing relay SYN² now energized the code transmitting circuit is completed at the contact 146 of this relay SYN², the specific code of impulses necessary to close selector contact 70 of relay CRR² is then transmitted to the tower to cause the red lamp R² to be energized in a manner and for reasons already explained. With the hold-over relay HO² now again de-energized it will not be able to permit the operation of the code transmitter CT² to be carried past the point 35 at which the contacts 96—125 assume their left hand position. The pilot relay PR² is therefore re-energized at the end of this cycle of operation of the code transmitter CT² due to shifting of contacts 96—125 and opening of contacts 114, 40 and all of the apparatus associated therewith is returned to its normal condition, in which it has been shown.

In the particular embodiment of the invention illustrated the coding wire comprises the telephone line TEL simplex. This simplexing of the telephone line is accomplished by bridging impedances 15, 15^a, 15^b, etc. across the telephone line, and in connecting the circuit portions of the coding circuit to the midpoint of these impedances. It is of course understood that due to neutralization the coding impulses in an arrangement of this kind the impulses will not interfere with simultaneous telephone communication. On the other hand, if desired, the coding circuit may 55 comprise a separate line wire and the common return wire C, if desired.

In the specific dispatcher's office equipment illustrated in Fig. 1A of the drawings the relays RG² and RR², if once picked up remain, stuck up 60 until manually restored. If automatic restoration or de-energization is desired, the stick circuit (see Fig. 2) for the relay RG² may be carried through back contact 190 of the relay RR², and similarly the stick circuit for the relay RR² may 65 be carried through a back contact 190^a of the stick relay RG². Suitable single stroke audible signals GA and RA, which sound only upon being energized may be connected in series with the lamps R² and G², if desired. With this modified 70 construction the lamps R² and G² of the miniature track layout would at all times indicate the condition of occupancy of the corresponding detector track circuit, and the audible signal would sound upon each change of indication. This 75 modified form of the circuit arrangement for the

relays RG² and RR² has been shown in Fig. 2 of the drawings.

Further it should be understood that, even though in the arrangement shown provision has only been made for the indication of occupancy 5 of detector track circuits associated with track switches, the form of indication illustrated may be carried much further. For instance, any other track circuit may be indicated in the same way; and further if desired the position of track 10 switches and derails, and the indicating condition of signals may be indicated in the same way.

It is of course noted that the lock-out arrangement including the pilot relays PR prevents two codes being transmitted to the dispatcher's office 15 at the same time. Also, as heretofore pointed out, the cut-out relays COR located in the tower prevents an OS-ing code being transmitted from a waystation to the dispatcher's office at a time when the dispatcher is transmitting a control 20 code to one of the waystations. This cutout relay COR, of course, by itself is not able to prevent the dispatcher from transmitting a control code when an OS-ing code is being received, and for this reason the operator must assure himself 25 that there is no OS-ing code being transmitted when he starts to transmit a control code. This may be accomplished by listening in on a telephone connected across the coding circuit, or in any other suitable or practical way. On the other 30 hand, if desired, instead of using the cut out relay COR a pilot relay PR may be used, which has contacts associated therewith which open all of the circuits leading to the dispatcher's calling key or lever code contacts, so that the dispatcher can 35 not transmit a control code when excess energy exists in the lock-out circuit LO.

Referring to Fig. 1B of the drawings the dotted polygon CT¹ is intended to conventionally represent the OS-ing mechanism associated with the 40 track switch S¹, and the rectangle 200 is intended to conventionally represent the control mechanism for controlling the switch machine and signals associated with the switch S².

It should be understood that the present invention is also applicable to double track systems and that cross-overs may be operated in substantially the same way as single end switches are operated, suitable approach locking of course being used in each case in a manner and for 50 reasons indicated in the application heretofore referred to. It may also be pointed out here that instead of using a metallic common return wire C, as shown, ground plates or cones and an earth return connection may be used, if desired. 55

Having thus shown and described one specific embodiment of a portion of a train dispatching system embodying my invention in which certain parts and devices have been shown conventionally, it is desired to be understood that the particular arrangement illustrated has been selected for the purpose of enabling the features of the invention to be described, and has not been selected with the intent of showing the scope of the invention or the particular apparatus preferably employed in practicing the same; it is therefore desired to be understood that various changes, modifications and additions may be made to adapt the invention to the particular signalling system and the particular track layout where the 70 invention is to be practiced, all without departing from the spirit or scope of the invention or idea of means underlying the same, except as demanded by the scope of the following claims.

1. In an OS-ing system for indicating the condition of occupancy of a plurality of track circuits of which more than one of said track circuits may become occupied or unoccupied simultaneously, 5
5. the combination with a railway system, of a plurality of track circuits each including the usual track relay and track circuit source of current, a single line circuit associated with all of said track relays and a local office, code responsive means at 10
10 said office for giving an indication depending on the character of code received over said line circuit from one of said track circuits in response to a change in the condition of its track relay, code impulse sending means located at each of said 15
15 track circuit locations for transmitting to said code responsive means over said line circuit distinctive electric code impulses upon each change in the condition of the corresponding track relay, and a lockout circuit and associated relays active when 20
20 one code impulse sending means is active to prevent all other code impulse sending means from sending any impulses over said line circuit.
2. In combination with a railway system, a plurality of way stations located at different remote points along a railway track, a local dispatcher's office, a line circuit connecting said way stations and office, code responsive selecting relays in said office, a lockout circuit connecting all of said way stations and office, an automatically operated transmitting means located at each of said way stations comprising; a motor driven code transmitter for intermittently completing said line circuit to simulate a code for each cycle of operation thereof, a normally energized lockout 25
25 relay in said lockout circuit for preventing a code being transmitted by said transmitter, means for energizing said lockout circuit with excess energy in response to movement of a particular lockout relay to its retracted position, said excess energy 30
30 being sufficient in value to prevent any other lockout relay being moved to the retracted position, and means for initiating said code transmitting means and causing said lockout relay to assume its retracted position. 35
35
3. In combination with a railway system, a plurality of way stations located at different remote points along a railway track, a local dispatcher's office, a line circuit connecting said way stations and office, code responsive selecting 40
40 relays in said office, a lockout circuit connecting all of said way stations and office, an automatically operated transmitting means located at each of said way stations comprising; a motor driven code transmitter having a plurality of separate 45
45 interrupters each of which is adapted to intermittently complete said line circuit in code fashion for each cycle of operation thereof if selected, a normally energized lockout relay in said lockout circuit for preventing a code being transmitted by said transmitter, means for energizing said lockout circuit with excess energy in response to actuation of a particular lockout relay to its retracted position, means for selecting one of said interrupters, initiating the associated code transmitting means and causing the associated lockout relay to assume its retracted position in 50
50 response to a change of traffic conditions. 55
55
4. In combination with a railway system, a plurality of way stations located at different remote points along a railway track, a local dispatcher's office, a line circuit connecting said way stations and office, code responsive selecting relays in said office, a lockout circuit connecting all of said way stations and office, an automatically operated code transmitting means located at each of said 60
60
- way stations comprising; a motor driven code transmitter for intermittently completing said line circuit to simulate a code for each cycle of operation thereof, a normally energized lockout relay in said lockout circuit for preventing a code being transmitted by said transmitter, means for energizing said lockout circuit with excess energy in response to movement of a particular lockout relay to its retracted position, said excess energy being sufficient in value to prevent any other lockout relay being moved to the retracted position, means for initiating said code transmitting means and causing said lockout relay to assume its retracted position, and means for stopping said code transmitter after one complete code of impulses has been transmitted. 65
65
5. In combination with a railway system, a plurality of way stations located at different remote points along a railway track a local dispatcher's office, a line circuit connecting said way stations and office, code responsive selecting relays in said office, a lockout circuit connecting all of said way stations and office, an automatically operated code transmitting means located at each of said way stations comprising; a motor driven code transmitter having a plurality of separate interrupters each of which is adapted to intermittently complete said line circuit in code fashion for each cycle of operation thereof if selected, a normally energized lockout relay in said lockout circuit for preventing a code being transmitted by said transmitter, means for energizing said lockout circuit with excess energy in response to actuation of a particular lockout relay to its retracted position, means for selecting a particular interrupter of said code transmitting means and for initiating said code transmitting means and for causing said lockout relay to assume its retracted position, and means for stopping said code transmitter at the end of its operating cycle as soon as a complete code has been transmitted since its initiation. 70
70
6. In combination with a railway system, a plurality of way stations located at different remote points along a railway track a local dispatcher's office, a line circuit connecting said way stations and office, code responsive selecting relays in said office, a lockout circuit connecting all of said way stations and office, an automatically operated transmitting means located at each of said way stations comprising; a motor driven code transmitter having a plurality of separate interrupters each of which is adapted to intermittently complete said line circuit in code fashion for each cycle of operation thereof if selected, a normally energized lockout relay in said lockout circuit for preventing a code being transmitted by said transmitter, means for energizing said lockout circuit with excess energy in response to actuation of a particular lockout relay to its retracted position, a motor driven code transmitter for intermittently completing said line circuit for each cycle of operation thereof, traffic controlled means for initiating said code transmitter, a normally energized lockout relay in said lockout circuit for preventing a code being transmitted by said code transmitter in spite of its operation thereof, said lockout relay being urged to its retracted position in response to operation of said traffic controlled means but assuming its retracted position only in the event said lockout circuit is not energized by excess current, means for energizing said lockout circuit by excess current upon the retraction of one of said lockout relays, means for stopping 75
75

- said code transmitter at the end of the first cycle of operation during which a code is being transmitted, and other means for allowing said code transmitter to operate through an additional 5 cycle of operation in the event that the lockout relay is held in its normal position by excess energy and is allowed to assume its retracted position during an intermittent point in the cycle of operation of said code transmitter.
10. 7. OS-ing means for railway systems comprising, two indicators, a stick relay for each of said indicators, said indicators being located in a dispatcher's office and if active indicating respectively the occupancy and unoccupancy of 15 a distant track circuit, a code responsive selecting relay having contacts associated therewith of which one is momentarily closed to pick up one of said stick relays in response to one distinctive code and then another contact is momentarily 20 closed to pick up the other stick relay in response to another distinctive code, a track relay for said distant track circuit, other transmitting means for transmitting one distinctive code upon de-energization of said track relay and for transmitting another distinctive code upon energization of said track relay, and a back contact for 25 each of said stick relays in the stick circuit of the other stick relay, whereby the picking up of one stick relay automatically drops the other 30 stick relay.
8. In an OS-ing system for indicating conditions of traffic along a railway track, the combination with a railway track, of a plurality of way stations along said track, a local dispatcher's office, a line circuit connecting all of said way stations and said office, means at each of said way stations for transmitting a distinctive code of impulses to said office in response to conditions of traffic at such way station, code 35 impulse responsive means at said office for giving an indication depending on the character of the code of impulses received, and lockout means for preventing a code of impulses being transmitted from one way station while a code of 40 impulses is transmitted from another way station including a normally energized relay at each way station which if energized by excess current will prevent said way station transmitting a code of impulses.
50. 9. In a train dispatching system, the combination with a plurality of way stations and a dispatcher's office, of a track circuit at each way station including a normally energized track relay, two stick relays associated with each of said 55 track relays, a pick-up circuit for each of said two stick relays, means for momentarily closing one of said pick-up circuits when the associated track relay is de-energized and for momentarily closing the other pick-up circuit when the 60 associated track relay is energized, a stick circuit for each stick relay, and means for indicating in the dispatcher's office the condition of energization of said stick relays.
10. In a train dispatching system, the combination with a plurality of way stations and a dispatcher's office, of a track circuit at each way station including a normally energized track relay, two stick relays for each of said track relays, a pick-up circuit for each of said two stick relays, 65 means for momentarily closing one of said pick-up circuits when the associated track relay is de-energized and for momentarily closing the other pick-up circuit when the associated track relay is energized, a stick circuit for each stick relay, and means for indicating in the dispatcher's office the 70
- condition of energization of said stick relays, and means for breaking said stick circuits when the condition of said stick relays has been indicated in said office.
11. In a system for controlling track switches, a central office, a distant way station, a track switch at said way station, a switch machine for operating said track switch, a telephone line connecting said office and switch machine and having a telephone receiver at said central office, a control circuit for operating said switch machine, and means associated with said switch machine for intermittently applying current characterizing a particular code to said telephone receiver while said switch machine is operated from one 15 to the other extreme position.
12. In a system for controlling track switches, a central office, a distant way station, a track switch at said way station, a switch machine for operating said track switch, a telephone line connecting said office and switch machine and having a telephone receiver at said central office, a control circuit for operating said switch machine, and means associated with said switch machine for intermittently applying current to 20 simulate a particular code to said telephone receiver while said switch machine is operated from one to the other extreme position.
13. In a system for controlling track switches, a central office, a distant way station, a track switch at said way station, a switch machine for operating said track switch, a telephone line connecting said office and switch machine and having a telephone receiver connected to the office 25 end thereof, a control circuit consisting of said telephone line simplex and a common return wire for controlling the operation of said switch machine, and means associated with said switch machine for intermittently applying current to 30 said telephone receiver while said switch machine is operated from one to the other extreme position.
14. In a system for controlling track switches, a central office, a distant way station, a track switch at said way station, a switch machine for operating said track switch, a telephone line connecting said office and switch machine and having a telephone receiver connected to the office 35 end thereof, a control circuit consisting of said telephone line simplex and a common return wire for controlling the operation of said switch machine, and means associated with said switch machine for intermittently applying current to 40 said telephone receiver while said switch machine is operated from one to the other extreme position.
15. In combination, a railway track switch having a normal and a reverse position, a normal control relay for said switch, a reverse control relay for said switch, a polarized relay, a normal control circuit for said polarized relay controlled by a front contact of said normal control relay, a reverse control circuit for said polarized relay controlled by a front contact of said reverse control relay and a back contact of said normal control relay, and means for operating said switch to 50 its normal or its reverse position according as said polarized relay is energized in the normal or the reverse direction.
16. In a centralized traffic control system for railroads, a plurality of traffic controlling signals for establishing a corresponding number of routes over a trackway, a plurality of neutral relays one for clearing each route and one for all routes at stop, energizing circuits for each of said 55
- 75

signals closed only when the neutral relay for the corresponding route is energized and that route is set up over the trackway, means for selectively energizing any particular neutral relay, 5 and means allowing only one of said neutral relays to be energized at a time, whereby any route may be cleared, and whereby any cleared route may be put to stop.

17. In a dispatching system for railroads, a 10 track switch, a plurality of signals governing traffic over said track switch, a route storing relay for each of said signals, a stop route relay, a dispatcher's office, a code transmitting means manually governable in said dispatcher's office 15 for transmitting any one of a plurality of series of code impulses, code receiving means at said track switch for selectively energizing a particular route storing relay or said stop route relay in accordance with the particular one of said 20 plurality of series of code impulses, a stick circuit for each route storing relay including its own front contact and a back contact of said stop route relay, and a circuit closed by each route storing relay when energized for clearing its associated signal only when said track switch is in 25 alignment for the corresponding route.

18. In a centralized railway traffic controlling system of the selector code type, the combination with a relay having a control winding and a 30 holding winding, a circuit for said control winding including a source of direct current, a circuit for said holding winding including a front contact of said relay and a source of direct current of fixed polarity, whereby if said holding circuit 35 is closed the closing of said control circuit will result in de-energization of said relay if said first mentioned source is of a particular polarity.

19. In combination, a railway track switch having a normal and a reverse position, a normal 40 control relay for said switch, a reverse control relay for said switch, a polarized relay having contacts which are operated to a position depending on the polarity of the current temporarily applied to the relay and which remain in said 45 position until current of reverse polarity is applied to the relay, a normal control circuit for said polarized relay controlled by a front contact of said normal control relay, a reverse control circuit for said polarized relay controlled by 50 a front contact of said reverse control relay and a back contact of said normal control relay, and means for operating said switch to its normal or its reverse position according as said polarized 55 relay is energized in the normal or the reverse direction.

20. In a centralized traffic control system for railroads, a track layout including a track switch for establishing a plurality of routes through said track lay-out, a switch machine for operating 60 said track switch, a signal at the entrance point to each route for when indicating proceed allowing a train to move over said route, a route relay for each route, a circuit for operating said switch machine to a position to establish a particular 65 route closed only if the corresponding route relay is energized, a circuit for causing a particular signal to indicate proceed closed only if the route at the entrance to which said signal is located is established and then only if the corresponding 70 route relay is energized, and means for manually controlling said route relays.

21. In a centralized traffic control system for railroads, a track lay-out including a track switch for establishing a plurality of routes through said 75 track lay-out, a switch machine for operating

said track switch, a signal at the entrance point to each route for when indicating proceed allowing a train to move over said route, a route stick relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, and pick-up circuits for said stick route relays so controlled that only one of said stick route relays can be picked up at one time. 5

22. In a centralized traffic control system for railroads, a track lay-out including a track switch for establishing a plurality of routes through said track lay-out, a switch machine for operating said track switch, a signal at the entrance point to each route for when indicating proceed allowing a train to move over said route, a route stick relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, pick-up circuits for said stick route relays so controlled that only one of said stick route relays can be picked up at one time, and a stick circuit for each route relay including a back contact of each conflicting route relay. 10 20 25

23. In a centralized traffic control system for railroads, a track lay-out including a track switch for establishing a plurality of routes through said track lay-out, a switch machine for operating said track switch, a signal at the entrance point to each route for when indicating proceed allowing a train to move over said route, a route relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, a control circuit connecting said track lay-out and a distant office, and manually operable means for controlling said route relays over said control circuit. 35 40 45

24. In a centralized traffic control system for railroads, a track lay-out including a track switch for establishing a plurality of routes through said track lay-out, a switch machine for operating said track switch, a signal at the entrance point to each route for when indicating proceed allowing a train to move over said route, a route relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, code responsive means for controlling said route relays, and manually controlled means at a distant office for transmitting distinctive codes to said code responsive means for controlling said code responsive means and in turn said route relays. 55 60 65 70

25. In a centralized traffic control system for 75

5 railroads, a track lay-out including a track switch for establishing a plurality of routes through said track layout, a switch machine for operating said track switch, a signal at the entrance
10 5 point to each route for when indicating proceed allowing a train to move over said route, a route stick relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, code responsive means for controlling pick-up circuits for said route stick relays, and manually controlled means at a distant office for transmitting distinctive codes to said code responsive means for controlling said code responsive means and in turn said route stick relays.

15 26. In a centralized traffic control system for railroads, a track lay-out including a track switch for establishing a plurality of routes through

10 said track lay-out, a switch machine for operating said track switch, a signal at the entrance point to each route for when indicating proceed allowing a train to move over said route, a route stick relay for each route, a circuit for operating said switch machine to a position to establish a particular route closed only if the corresponding route relay is energized, a circuit for causing a particular signal to indicate proceed closed only if the route at the entrance to which said signal is located is established and then only if the corresponding route relay is energized, code responsive means for controlling pick-up circuits for said route stick relays, manually controlled means at a distant office for transmitting distinctive codes to said code responsive means for controlling said code responsive means and in turn said route stick relays, stick circuits for said route stick relays, and other means controlled by said code responsive means for breaking said 15 stick circuits.

20 BERNARD J. SCHWENDT.
